(57) **CLAIM**

The ornamental design of an open top wire basket lined with a fabric filter material for suspending within a storm sewer under a grate to collect sediment deposition, as shown and described.

DESCRIPTION

FIG. 1 is a perspective view of an open top wire basket lined with a fabric filter material for suspending within a storm sewer under a grate to collect sediment deposition showing my new design;

FIG. 2 is a side view thereof, the opposite side view being a mirror image;

FIG. 3 is an end view thereof; the opposite end view being a mirror image;

FIG. 4 is a top view thereof; and,

FIG. 5 is a bottom view thereof.

The cross-line pattern, which is partially shown for ease of illustration, represents a conventional fabric and is understood to repeat uniformly throughout the indicated area.
